BOWLING SLIDE RULE

Marshall Hertig, Minneapolis, Minn.

Application September 7, 1948, Serial No. 48,138

8 Claims. (Cl. 235—70)

1

This invention relates to a computing device for the rapid computation of data which will enable bowlers consistently to bowl high scores.

Bowling alleys are constructed of hard wood according to specifications defined by official regulations. The alleys are 63 feet long and not less than 41 nor more than 42 inches in width.

At the front end of each alley there is provided a space not less than 15 feet long called the approach and is separated from the alley by a foul line. At the far end of the alley the pins are arranged in a triangular array. From center to center the pins are placed 12 inches apart. The bowling balls are not greater than 27 inches in circumference.

The object of the game is to knock down the pins by rolling the bowling ball along the alley. Each player is allowed two bowls to accomplish this. If all of the pins are knocked down on the first ball it is considered a "strike" and the bowler is credited with the ten pins plus the number of pins he knocks down with his next two balls. If, however, on his first try, he leaves some pins standing, he must use his second ball, and if he succeeds in knocking down the remaining pins he is credited with a "spare" and his score is 10 pins plus what he makes on his next ball.

The majority of the expert bowlers are "spot" bowlers. A "spot" bowler will pick a spot from 12 to 24 feet down the alley and concentrate his aim only on this spot over which his ball must pass. He will not look at the pins until he has released the ball. This spot and the bowler's position at the time of delivery of the ball vary depending on which pin or group of pins he wishes to knock down.

The principal object of the computer of this invention is to locate the spot over which the bowling ball must pass and the position the bowler must start his approach from in order to knock down any given pin or group of pins remaining after the first ball has been delivered.

Another object of the invention is to provide a computer that is simply and speedily operated and will give directly both spot positions and starting positions at the same time.

A further object of the invention is to provide a computer that can be readily adapted to compute spot and starting positions on "duck pin" alleys.

These and other objects and advantages are attained by the computer of the invention which includes a base member marked with indicia representing preselected points corresponding to a plurality of directional lines of travel of a bowling

2

ball, for example, starting positions on a pre-selected starting line or strike points on a pre-selected strike line or both, a slide member movable relative to the base member marked with indicia indicating relative pin positions, and a cursor slidably mounted on the base member indexed to indicate corresponding pin positions on the slide member and points, for example, starting positions or strike points or both, on the base member.

The invention will be more particularly described with reference to the illustrative embodiment of the invention shown in the accompanying drawings in which:

15 Fig. 1 is a plan view of a computer embodying the principles of this invention.

Fig. 2 is an end view of the computer.

Fig. 3 is a diagrammatic plan view of a bowling alley.

20 Fig. 4 is an enlarged fragmentary plan view showing the computer set to indicate the corrected strike spot and starting point for a center delivery bowler using the 12 foot starting line to enable him to hit the number 10 pin.

25 In the bowling computer illustrated in Figs. 1, 2 and 4, 11 is the base member which may be constructed of any suitable material such as wood or plastic, 12 is a slide of similar material movable relative to the base 11 and adapted to slide in grooves 13 and 14, and 15 is a transparent cursor slidably mounted on the base 11 in a manner well known in the art.

30 In Fig. 3 of the drawing 16 represents a regulation bowling alley with approach space 17, foul line 18 and bowling pin positions 19. Dotted lines 20, 21 and 22 represent the 12, 14 and 16 foot starting lines while 23, 24, 25, 26, 27, 28 and 29, represent the 12, 14, 16, 18, 20, 22, and 24 foot spot lines as measured from the foul line 18.

35 Base member 11 carries three sets of index lines in sections A, B, and C, of the base member. The index lines in section A are based on the 12 foot starting line 20, in section B on the 14 foot starting line 21, and in section C on the 16 foot starting line 22. In each set, lines a, b, c, d, e, f, and g represent the 12, 14, 16, 18, 20, 22, and 24 foot spot lines 23, 24, 25, 26, 27, 28, and 29, and are marked to indicate inches of lateral adjustment along the respective spot lines. Lines a¹, b¹, c¹, d¹, e¹, f¹ and g¹ are marked to indicate inches of lateral movement along the starting line for bowlers using the 12, 14, 16, 18, 20, 22 and 24 foot spot lines 23, 24, 25, 26, 27, 28 and 29, respectively.

40 Sections A, B, and C are divided by center lines 31

which provide reference indexes or "standard spots" when setting slide 12.

Slide member 12 carries three sets of indicia D, E and F, each set representing relative projected pin sizes and positions as seen by a bowler using right side, center, or left side delivery, respectively. The individual pins are numbered on the drawings in accordance with the standard convention.

Cursor 15 is marked with an index G indicating the center line h and extremities i and i' of a bowling ball 30 relative in size to the sets of pin projections D, E, and F.

The amounts of the shifts in spot position or starting position necessary to hit a selected point in the pin array may be calculated from the proportions between the alley dimensions and the amount of deviation of the ball from the head or number 1 pin. The desired ball deviations v are conveniently measured on projections of the pin positions upon a line 32 (Fig. 3) passing through the front point of the head pin transversely of the alley. The shift in spot position s required for any desired ball deviation v is then given by the equation

$$s = \frac{vl}{m}$$

wherein l is the distance from the starting line to the spot line and m is the distance from the starting line to line 32. The shift in starting position j required for any desired ball deviation v is given by equation

$$j = \frac{vl}{n}$$

wherein l is the distance from the starting line to the spot line and n is the distance from the spot line to line 32.

Lines $a \dots g$ and $a' \dots g'$ are marked in scaled units representing actual distances s and j on the spot lines and starting lines, respectively. The scales may be marked by setting the slide of the computer with the center line 31 of the base member at the "strike" position, that is, at the point the bowler would wish to hit if all the pins were standing and he desired to make a "strike," and then by setting the center line h of the cursor 15 at successive selected points in the pin array and marking the scales $a \dots g$ and $a' \dots g'$ with values for distances s and j , calculated for corresponding values of the ball deviations v as indicated above. The scales may also be marked off by means of suitable templates laid out geometrically on the same principles.

One example of the use and operation of the computing device of this invention is illustrated in Fig. 4. In the illustrative problem shown the bowler is using the 12 foot starting line, section A of base member 11, the 18 foot spot line represented by lines d and d' , and center delivery section E of slide 12. The pin to be knocked down is number 10. In order to locate the required starting position along the 12 foot starting line or the new spot point on the 18 foot spot line, slide 12 is moved to the left until the representative pins, of section E, for center delivery, are aligned with section A of base member 11 representing the 12 foot starting line, in such a position that the center line 31 of section A indicates the "strike" position as defined above. Next the cursor 15 is positioned so that the center line h of representative ball 30 is directed at pin number 10 with the desired deflection or "English." From the projection of center line

5 upon line d of section A the bowler reads 5 inches, indicating that in order to hit the number 10 pin retaining his original starting position he must laterally shift the spot point the ball must pass over in order to hit pin 10, 5 inches to the right along spot line 26, or from the projection of center line h upon line d' the bowler reads 9 inches left indicating that if he retains his original spot point, he must laterally shift his starting position 9 inches to the left along starting line 20.

15 From the foregoing description it will be seen that the present invention provides a computing device for bowlers that will quickly and accurately locate the spot over which the bowling ball must pass or the position the bowler must start his approach in order to knock down any given pin or combination of pins enabling the bowler consistently to roll high scores.

20 It will also be evident that the base member, the slide and the cursor of the computing device comprise three relatively movable members and that the indicia thereon may be interchanged without departing from the invention. Moreover, it will be apparent that the invention may be embodied in computing devices of different but equivalent physical form, as for example, in a circular or cylindrical bowling slide rule equivalent to the linear device shown by way of illustration.

30 I claim:

1. A computing device for bowlers comprising a base member marked with indicia representing preselected points corresponding to a plurality of directional lines of travel of a bowling ball, a slide member movable relative to the base member marked with indicia indicating relative pin positions, and a cursor slidably mounted on the base member indexed to indicate corresponding pin positions on the slide member and points on the base member.

2. A computing device for bowlers comprising a base member marked with a direct reading scale representing starting positions on a preselected starting line, a slide member movable relative to said base marked with indicia indicating relative pin positions; and a cursor slidably mounted on said base member indexed to indicate corresponding pin positions on the slide member and starting positions on the base member.

3. A computing device for bowlers comprising a base member marked with a direct reading scale representing spot points on a preselected spot line, a slide member movable relative to said base marked with indicia indicating relative pin positions, and a cursor slidably mounted on said base member indexed to indicate corresponding pin positions on the slide member and spot points on the base member.

4. A computing device for bowlers comprising a base member marked with direct reading scales representing starting positions on a preselected starting line and spot points on a preselected spot line, a slide member movable relative to said base marked with indicia indicating relative pin positions and a cursor slidably mounted on said base member indexed to indicate corresponding pin positions on the slide member and spot points and starting positions on the base member.

5. A computing device for bowlers comprising a base member marked with direct reading scales representing starting positions on a preselected starting line and spot points on a preselected spot line, a slide member movable relative to said

base marked with three groups of indicia indicating relative pin size and positions as viewed from the right, the center and the left of the alley at the starting line and a cursor slidably mounted on said base member indexed to indicate corresponding pin positions on the slide member and spot points and starting positions on the base member.

6. A computing device for bowlers comprising a base member marked with direct reading scales representing starting positions on a preselected starting line and spot points on a preselected spot line, a slide member movable relative to said base marked with indicia indicating relative pin size and positions and a cursor slidably mounted on said base member indexed with transverse indicia indicating the center line and extremities of a bowling ball relative to the pin size and positions marked on said slide member to indicate corresponding pin positions on the slide member and spot points and starting positions on the base member.

7. A computing device for bowlers comprising a base member marked with a plurality of direct reading scales representing starting positions on a plurality of preselected starting lines and spot points on a plurality of preselected spot lines, a slide member movable relative to said base member marked with three groups of indicia indicating relative pin size and positions as viewed from the right, the center and the left

5

of the alley at the starting line, a cursor slidably mounted on said base member indexed with transverse indicia indicating the center line and extremities of a bowling ball relative to the pin size and positions marked on said slide member to indicate corresponding pin positions on the slide member and spot points and starting positions on the base member.

10

15

20
